UNITED STATES PATENT OFFICE.

JACOB BURKHARTZMEYER, OF FARIBAULT, MINNESOTA.

FOLDING CHAIR.

1,161,609.

Specification of Letters Patent. Patented Nov. 23, 1915.

Application filed May 9, 1913. Serial No. 766,501.

To all whom it may concern:

Be it known that I, JACOB BURKHARTZMEYER, a citizen of the United States, and a resident of Faribault, in the county of Rice and State of Minnesota, have invented certain new and useful Improvements in Folding Chairs, of which the following is a specification, reference being had to the accompanying drawings.

10 This invention relates to certain new and useful improvements in folding chairs.

The object of my invention is to provide a chair so constructed that when not in use, the same can be compactly folded, the construction being such however that when in use the chair will be firmly held to prevent accidental collapse.

With these and other objects in view the present invention consists in the combination and arrangement of parts as will be hereinafter more fully described and finally pointed out in the appended claims, it being further understood that changes in the specific structure shown and described may be made within the scope of the claims, without departing from the spirit of the invention.

In the accompanying drawings forming a part of this specification and in which like numerals of reference indicate similar parts 30 in the several views: Figure 1, shows a perspective view of a chair constructed according to my invention with portions broken away. Fig. 2, is a side view with parts 35 broken away showing the chair in folded position in dotted outline. Fig. 3, is a broken front view disclosing the seat as folded. Fig. 4, is a detail of the V-shaped spring. Fig. 5, is a detail of the socket lug.

40 In my present invention I provide a chair which when not in use can be compactly folded.

In the drawings the numeral 1, designates the back of the chair and 2, 2, the two rear 45 legs which are connected by means of the rear cross-bar 3. As shown in Fig. 2, one of the rear legs 2, is provided with a recess 4, having a laterally extending opening 1'. Secured to the rear chair legs 2, 2, are the 50 hinges 12, to which is secured the seat 19. By means of the hinges 21, the front legs 23, are secured to the seat 19. The front legs are braced near their lower ends by means of the rung 8'. As shown these front 55 legs 23, carry the hinges 24, giving support to the seat rungs 25, which by means of the

hinges 26, are secured to the rear legs 2. This construction permits the chair seat 19, being folded against the back 1, of the chair, as disclosed in dotted outline in Fig. 3. The 60 rear legs are strengthened at their lower ends by means of the rung 5'.

Held within the recess 4, is a V-shaped spring including the two members 5 and 7 the latter leaf of which being shorter in 65 length than the former, with an intermediate collar 6, through which passes a suitable securing pin 11, to hold this spring within the recess against casual displacement. The recess 4, is closed by means of the cover 3', 70 shown in Fig. 2. Extending from the stem 5, of the spring is the latching bolt 9, having its upper edge rounded, while its under edge is flat and projects forwardly a considerable distance beyond the outer surface of the leg. 75 This latching bolt 9, projects through the forwardly extending opening 1', in the manner shown in Fig. 2.

Held within the opening 9', and communicating with the recess 4, is the operating stem 10, by means of which the spring can be forced backward, to carry the latching bolt 9, rearward. The bolt 9 is normally held projected beyond the forward edge of the chair leg, as shown in Fig. 2 by the pressure of the contacting leaf of said spring. 80

Secured to the under face of the chair seat 19, is the lug or keeper 20, having a suitable socket with a flat bottom 4' the innermost point of which is radially a greater distance 85 from the pivot of the hinge of the bottom than the outermost point to prevent the outermost point of the lug from passing the innermost point of the latch when projected into said socket the entire distance. 90

As shown in Figs. 2 and 1, the chair legs 2, are provided with the stop shoulders 7', limiting the downward movement of the chair seat. The lug or keeper 20, is so positioned that the socket will be engaged by the latching bolt 9, when the seat is thrown downward into a working position of the chair, as is clearly shown in Fig. 2. The lower end x, of the socket 20, is arranged so that it will easily ride over the rounded edge 100 of the bolt 9, to force the same backward. After the bolt has found lodgment within the socket of the lug or keeper 20, the seat cannot be carried upward, and the chair is firmly held against casual collapse. 105

As shown in Fig. 3, the cross-bar 3, is provided with an aperture 2', across which ex- 110

tends the shaft 14, having the base 13. This shaft at one end is held by means of the staple 15, and coiled upon the shaft is the spring 16, one end 18, of which, normally 5 engages the chair seat 19, while the opposite end engages the bar 3, so that the spring normally exercises a tendency to force the seat upward. The chair seat being locked, should it be desired to fold the chair it is 10 simply necessary to shove the operating stem inward, to carry the bolt out of the lug. As soon as the bolt escapes, the spring 18, forces the seat upward, so that the seat will contact with the back 1, as disclosed in dotted 15 outline.

It is of course understood that chairs embodying my invention may be made in various sizes. The chair is further simple, and comparatively inexpensive in construction 20 and both durable and efficient in operation, and can be adjusted either into a folded or working position with ease, accuracy and despatch.

Having thus described my said invention 25 what I claim as new and desire to secure by United States Letters Patent is:

1. A folding chair having in combination, two rear legs, a cross bar connecting said legs, a seat hinged to said legs, two front 30 legs hinged to said seat, side rungs hingedly connected to each front and rear leg one of said rear legs having a recess with a forwardly extending opening, a V-shaped spring within said recess, a latching bolt secured to one end of said spring projecting through said opening, a keeper having a 35 socket secured to said seat, said bolt arranged to latch into said socket, and means for operating said spring whereby said 40 keeper may be released.

2. A folding chair having in combination, two rear legs, a rigid cross bar connecting said legs, a seat hinged to said legs, two front legs hinged to said seat, side rungs

hingedly connected to each front and rear 45 leg one of said rear legs having a recess with a forwardly extending opening, a V-shaped spring within said recess, a latching bolt having a flat keeper engaging portion secured to one end of said spring projecting through said opening, a pin extending laterally through the lower end of said spring, and means to operate said spring whereby said keeper may be released.

3. A folding chair having in combination, 55 two rigid rear legs, a rigid cross bar connecting said legs, a seat hinged to said legs, two rigidly connected front legs hinged to said seat, a side rung hingedly connected to each front and rear leg one of said rear 60 legs having a recess with a laterally extending substantially rectangular opening, a V-shaped spring within said recess, a flat sided latching bolt secured to one end of said spring projecting through said opening, 65 and a push stem secured to one end of said spring and located beneath said seat.

4. A folding chair having in combination, two rear legs, a cross bar connecting said legs, a seat hinged to said legs, two front 70 legs hinged to said seat, a side rung hingedly connected to each front and rear leg one of said rear legs having a recess with a forwardly extending opening, a V-shaped 75 spring having one leaf shorter than the other occupying said recess, a latching bolt secured to the longer leaf of said spring and projecting through said opening, a pin extending laterally through the junction of said spring leaves, and means to operate 80 said spring whereby said keeper may be released.

In testimony whereof I affix my signature, in the presence of two witnesses.

JACOB BURKHARTZMEYER.
